US0D1048579S

(12) United States Design Patent (10) Patent No.: US D1,048,579 S
(45) Date of Patent:  Oct. 22, 2024

(54) PET SEAT COVER

(71) Applicant: Ganzhou Lingyue Automotive Products Co., Ltd., Ganzhou (CN)

(72) Inventors: Jinjin Li, Ganzhou (CN); Qinghua Li, Ganzhou (CN)

(73) Assignee: Ganzhou Lingyue Automotive Products Co., Ltd., Ganzhou (CN)

() Term: 15 Years

(21) Appl. No.: 29/944,778

(22) Filed: May 30, 2024

(51) LOC (14) Cl. 30-01

(52) U.S. Cl.

USPC D30/118; D6/611

(58) Field of Classification Search

USPC D30/108, 118, 119, 199; D12/104, 416;

(57) CLAIM

The ornamental design for a pet seat cover, as shown and described.

DESCRIPTION

FIG. 1 is a first perspective view of a pet seat cover showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines and de-emphasized half tone portions illustrate portions of the pet seat cover that form no part of the claim design.

1 Claim, 8 Drawing Sheets
